Attorney

UNITED STATES PATENT OFFICE.

JAMES PRENDERGAST, OF SYRACUSE, NEW YORK.

BARREL-HOOP.

1,360,792.

Specification of Letters Patent. Patented Nov. 30, 1920.

Application filed November 10, 1917, Serial No. 201,307. Renewed August 20, 1920. Serial No. 404,960.

To all whom it may concern:

Be it known that I, JAMES PRENDERGAST, a citizen of the United States, residing at Syracuse, in the county of Onondaga and State of New York, have invented certain new and useful Improvements in Barrel-Hoops; and I do hereby declare the following to be a full, clear, and exact description of the invention, such as will enable others skilled in the art to which it appertains to make and use the same.

This invention relates to improvements in the manufacture of hoops, and more particularly to the manufacture of wooden hoops, although it is obvious from the following description that the same may be utilized in connection with the manufacture of hoops of any material.

It is well known that in methods heretofore employed in the manufacture of hoops, considerable expense is incurred and valuable time is consumed in skiving the opposed ends of the strip of material from which the hoop is made, and that when the ends are brought into the usual overlapping engagement with respect to each other, the joint is unduly thickened. Besides the expense incurred by this operation, there is considerable material wasted by overlapping the ends of the strip to form the joint in the hoop.

With these conditions in view, the invention contemplates the provision of means whereby the necessity of skiving the ends of the strip is eliminated and whereby the opposed ends of the strip are fastened in abutting engagement with respect to each other, thus saving the time and labor previously consumed in skiving the ends and saving the material formerly wasted by making an overlapping joint. To this end the invention provides a cleat designed to tie the ends of the strip together in abutting engagement with each other, the cleat being preferably of wood of the same width as the hoop, and may be of a thickness substantially less than that of the hoop. The invention also provides novel retaining means for securing the cleat to the hoop.

One embodiment of the invention is hereinafter fully described, illustrated in the accompanying drawings, and more particularly pointed out in the appended claims; it being understood that the drawings are for the purpose of illustration only and not as defining the limits of the invention. The

right is reserved to make such changes in minor details of construction and in proportion of parts as fairly fall within the scope of the appended claims without departing from nor sacrificing any of the advantages of the invention.

In the accompanying drawings:—

Figure 1 is a perspective view of a hoop constructed in accordance with the invention.

Fig. 2 is an outside elevation of the hoop joint.

Fig. 3 is a plan view of the joint.

Fig. 4 is an inside elevation of the joint.

Fig. 5 is a detail view of a retaining staple.

Like reference numerals are used to designate like parts throughout.

In the embodiment of the invention disclosed in the accompanying drawings, 1 designates a hoop constructed in accordance with this invention, wherein the ends 2 and 3 of the strip used in making the hoop are brought into abutting engagement with each other as shown at 4, and secured in said position by a cleat 5. The hoop is preferably made of a suitable kind of wood, although it is obvious that any other suitable material may be substituted therefor.

The cleat 5 may be of any suitable material, such as wood or metal, but is preferably made of a wood similar to that used in making the hoop. It is to be noted that the cleat may be and is preferably of a thickness considerably less than that of the hoop and of substantially the same width. This provides a substantially rigid joint which is considerably lighter than the usual joint wherein the ends of the strip are in overlapping engagement with each other.

The cleat 5 is shown provided with elongated tapering extremities 6, and with a wide centrally positioned portion 7, thereby providing means which will yield a relatively rigid joint, it being understood that the wide portion of the cleat is designed to coincide with the joint 4 and operating to reinforce the same. The cleat may be retained upon the hoop by a plurality of nails or screws 8 and staples 9, it being noted that the nails or screws 8 are positioned relatively close to the extremities 2 and 3 of the hoop, while the staples 9 are shown positioned adjacent the tapered extremities 6 of the cleat.

The staples are of a form best shown in

Fig. 5, as comprising a body portion 10 having integral depending tangs 11, designed to be driven into the material of the hoop on either side of the tapered ends 6. The body portion 10 of the staple is shown provided with a centrally positioned aperture 12 which is designed to receive an auxiliary nail or screw to thereby provide a reinforced fastening device for the end of the cleat.

10 It is to be understood that if the hoop is constructed of a material not adapted to receive driven fastening means such as hereinbefore described, suitable rivets may be used in lieu thereof without departing from the 15 spirit of the invention.

It is to be further noted that by means of the above described cleat and fastening means, many hoops which have become split or broken through use and which would 20 otherwise be discarded as useless, may be readily and quickly repaired and made substantially as good as new.

From the above description, it will be seen that a hoop joint has been provided that 25 eliminates all skiving or overlapping of the ends of the strip used in making the hoop; that produces a hoop equally as strong, neater in appearance, and lighter in weight than was possible by methods heretofore employed, and that is substantially cheaper and 30 easier to manufacture.

Having thus described the invention, what is claimed as new is:—

1. A hoop formed from a strip of resilient

material, said strip being bent to bring its 35 opposed ends into abutting engagement with respect to each other, a cleat provided with a broad central portion, and tapering extremities, said broad portion designed to coincide with the joint in the hoop, means 40 to secure the ends of the strip to said broad portion of the cleat, and similar staples straddling and securing the tapered extremities of the cleat to the hoop on opposite sides of the joint.

2. In a hoop having a non-overlapped or abutting joint, a cleat positioned over the joint, said cleat having a broad central portion coinciding with the joint, and tapered extremities disposed on opposite sides of the 50 joint, means to retain the ends of the hoop to the broad portion of the cleat, and similar staples straddling and securing the ends of the cleat to the hoop at points removed from the joint and on opposite sides thereof.

3. In combination with a hoop, a cleat to cover the joint therein on the outside of said hoop, said cleat being relatively thin and of uniform thickness throughout and provided with elongated tapered extremities, 60 means to retain the cleat to the hoop, similar means designed to straddle the ends of said cleat and be driven into the hoop, and retaining means to simultaneously engage the cleat, the hoop and said straddling means.

In testimony whereof, I affix my signature.

JAMES PRENDERGAST.
